Fig. 1.

Fig. 2.

FIG. 3.

FIG. 4.

FIG. 1 is a front perspective view of a sewing machine carrying case or similar article showing our new design;

FIG. 2 is a top plan view thereof;

FIG. 3 is a rear elevation thereof, the broken line showing of the base having been omitted for convenience of illustration;

FIG. 4 is a bottom plan view thereof of FIG. 3; and

FIG. 5 is an elevation of the end opposite that seen in FIG. 1.

The dominant features of the design reside in the full line portions of the drawing, a conventional base being shown in broken lines.

We claim:

The ornamental design for a sewing machine carrying case or similar article, as shown and described.
